UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Original application filed August 2, 1923, Serial No. 655,240. Divided and this application filed April 7, 1924. Serial No. 704,676.

To all whom it may concern:

Be it known that I, HAROLD G. WARR, a citizen of the United States, residing at Park Ridge, in the county of Cook and State of Illinois, have invented certain new and useful Improvements in Rail Anchors, of which the following is a specification.

My invention relates to anchoring devices and more particularly to the one-piece type 10 of anchor in which jaws for gripping opposite edges of the rail base are differentially disposed with relation to a part of the device adapted to bear against the bottom surface of the rail so that movement 15 of the anchor transversely of the rail distorts the device and effects a spring grip on the upper and lower surfaces of the rail base.

Prior to this invention, it has been customary in manufacturing devices of the above character to so form the jaw portions thereof as to utilize the upper inclined surfaces of the rail base as cams to effect a distortion of the yoke when the same is driven 25 transversely of the rail to its applied position. Therefore, in order to obtain maximum efficiency of anchors of the above general type (the anchors relying upon their 30 resiliency to maintain the desired grip on the rail), it is necessary that they be manufactured accurately and be subjected only to a limited distortion during their applications to a rail. Such accuracy is difficult to maintain in the manufacture of anchors of 35 the configuration heretofore used. Furthermore, efficiency of such anchors properly formed is often impaired by excessive distortion resulting from improper application of the anchors to their gripping positions.

40 A primary object of the invention is to provide a rail anchor of the above general type, that may be more easily and efficiently manufactured, made with a higher average of perfection as to its rail gripping portions 45 and which when applied to a rail will firmly grip the upper and lower surfaces of the rail base.

One of the specific objects contemplated by this invention includes the provision of 50 a one-piece rail anchor device in which the jaw portions are so formed with respect to the part of the anchor for bearing against the under surface of the rail as to effect

the desired grip of the device on the rail independently of the inclination of the upper 55 surfaces of the rail base.

A further and more specific object of my invention is to provide an anchor device in which the jaw portions are so formed with relation to each other and to the bottom 60 surface of the rail and so differentially disposed with relation to the part of the device for bearing against the under surface of the rail base that the grip of the anchor of the rail is effected both by reason of said 65 differential position of the jaws and by reason of the relative angle of the jaws with relation to the bottom surface of the rail base.

Another effect is to provide an anchor of 70 the above general character with means for indicating its proper gripping position on a rail and for preventing movement of the anchor beyond its intended applied position 75 so as to avoid excessive distortion of the anchor during its application to a rail.

The invention has for further objects such other new and improved arrangements and constructions as will be hereinafter described and claimed for carrying out the 80 above stated objects and such other objects as will appear from the following description of the invention.

The invention is illustrated in a preferred embodiment in the accompanying drawings, 85 wherein

Fig. 1 is a side view in elevation of a rail anchor constructed in accordance with my invention, applied to its operative position on a rail base.

Fig. 2 is a similar view in elevation of the anchor applied to its initial position on the rail and before the anchor is subjected to any appreciable stress, and

Fig. 3 is a plan view of the elements il- 95 lustrated in Figs. 1 and 2, the anchor device being illustrated in this figure in its applied position.

In the drawing the reference numeral 10 indicates the lower portion of a railroad 100 rail, and 11 one of the cross ties on which the rail is supported.

The anchor is designated generally by the reference numeral 12 and is preferably formed from a steel bar bent to provide a 105 relatively large hook shaped jaw portion 13

and a smaller jaw portion 14 for engaging opposite edges of the rail base 10 and with an inverted V-shaped portion 15 intermediate the jaws for bearing against the under 5 surface of the rail base. The V-shaped portion preferably bears against the bottom surface of the rail nearer the jaw 14 than the jaw 13 so that movement of the anchor transversely of the rail, for example, toward 10 the right of Fig. 2, effects a differential leverage between the jaws and thereby distorts the anchor and produces a firm spring grip of the device on the rail.

The jaws 13 and 14 are provided with inclined surfaces 16 and 17 which function as moving cams and cooperate with the differential arrangement of the jaws, during the application of the anchor, to effect the desired gripping action. The extremity of 15 jaw 13 is provided with an inclined surface 18 which, together with the inclined surface 17, of jaw 14, normally stands at a slightly greater angle than the inclined upper surfaces of the rail base so as to confine the 20 engagement of the jaws to substantially the upper corners of said rail base. The angle of the inclined surface 17 of jaw 14 is preferably, though not necessarily, slightly greater than the angle of the surface 16 25 of the jaw 13 so as to increase the gripping action of the anchor during its application to the rail. By providing the anchor with the inclined surfaces above described, the vertical distance between the V-shaped portion 15 and the portion of the jaws engaging the upper surfaces of the rail base may be more accurately controlled and at the 30 same time compensate for variations in the thickness of the rail base and in variations 35 in the slope of the inclined upper surfaces 40 of the rail base.

In applying devices of the general character to which this invention appertains, the workmen often drive the device beyond its 45 intended normal position, thereby subjecting the small jaw and other parts of the anchor to greater distortion than is intended. This is particularly true in connection with the type of anchor in which 50 the end of the larger jaw is recessed or otherwise formed to provide an abutment, or shoulder, adapted to assume a position against the vertical edge of the rail base when the anchor reaches its operative position. With such structure, the stress on the 55 anchor is somewhat relieved as soon as the edge of such recess snaps over the edge of the rail base, and in such case, the hammer blow intended to drive it home, often forces 60 it upon the rail to a point beyond its intended position. Excessive distortion of rail anchors of the above character impairs 65 their resilient rail-gripping qualities and makes them unsuitable, when removed, to be applied to other rails. I overcome the

above mentioned and other incidental objections to anchors of this general type by providing the undersurfaces of both jaws 13 and 14 with relatively abrupt shoulders 19 and 20 adapted to abut against opposite 70 edges of the rail base when the anchor is in its applied position. These shoulders, in addition to serving the useful purpose above mentioned, prevent the anchor from shifting transversely of the rail in either 75 direction from its applied position, and also provides suitable means for giving the workmen a visual indication as to when the anchor is nearing its applied position.

In applying my improved anchors to a 80 rail, the larger jaw is first hooked over one flange of the rail base and the other end is raised until the jaw 14 clears the upper edge of the opposite flange of said base. In this position of the anchor the V-shaped portion 85 15 will engage the under surface of the rail base, but the anchor will normally be loose on the rail. To tighten the anchors the device is driven in the direction of its length transversely of the rail, for example, 90 toward the right of Fig. 2, so as to force the cam surface 17 over the upper corner of the rail base. When the anchor is driven home, the shoulder 19 snaps down over one edge of the rail base and the shoulder 20 95 abuts against the opposite edge of said base, thereby providing means for locking the anchor in its applied position. The inclination of the surface 18 and likewise of the surface 17 insures a firm engagement of the 100 jaws with the rail base adjacent the shoulders. This construction insures that the shoulder 19 will snap down over the edge of the rail and that both shoulders will properly function to lock the anchor 105 against movement in either direction transversely of the rail.

This application is a division of my co-pending application, Serial 655,240.

I do not claim herein the method employed in the manufacture of the anchor device herein shown. The said method is described and claimed in my copending application Serial No. 708,493.

I claim:

1. A rail anchor adapted to be driven transversely of a rail to its applied position comprising a rail base embracing yoke provided with jaws having portions for engaging the upper surfaces of a rail base adjacent opposite edges thereof and with abutments adapted to bear against the vertical edges of the said base; the body of the yoke being bent to provide a seat adapted to bear against the under-surface of the rail base at a point nearer one of said jaws than the other.

2. A rail anchor comprising a yoke formed with jaws to engage the upper surfaces of a rail base at opposite edges there-

of and with means for bearing against the under surface of the base; said jaws being differentially disposed with relation to said bearing means to effect distortion of said yoke when the yoke is driven transversely of the rail, and one of said jaws being formed with an abutment adapted to engage the edge of the rail to limit the applying movement of said anchor.

10. 3. A one piece rail anchor adapted to be driven transversely of a rail to its applied position comprising a yoke formed by bending a metal bar to provide jaws for engaging the upper surfaces of a rail base and to provide a seat adapted to bear against the under surface of said rail; said seat portion being formed nearer one of said jaws than the other so as to make it necessary to stress said yoke when applying it to its operative position and said jaws being provided with shoulders adapted to engage the opposite vertical edges of the rail base to prevent movement of the anchor transversely of the rail in either direction from its applied position.

4. A rail anchor adapted to be driven transversely of a rail to its applied position comprising a yoke member formed with jaw portions to engage the upper surfaces of a rail base and with means for bearing against the under surface of said base; said bearing means being arranged nearer one of said jaws than to the other and said jaws being each provided with a shoulder adapted to abut against an edge of the rail base when the anchor is in its applied position.

5. A rail anchor comprising a yoke member formed with jaws for engaging opposite edges of a rail base and means for bearing against the bottom surface of the rail at a point nearer one of said jaws than the other; said jaws being formed with inclined surfaces to confine their engagement with the rail base to substantially the upper corners thereof when the yoke is in its applied position.

6. A rail anchor comprising a yoke member formed with jaws adapted to engage opposite edges of a rail base and with means for bearing against the bottom surface of the rail at a point nearer one of said jaws than the other; said jaws being formed with surfaces which normally stand at a greater

angle than the inclined surfaces of the rail base.

7. A rail anchor comprising a yoke member formed with jaws for engaging opposite edges of a rail base and with means for engaging the bottom surface of the rail at a point nearer one of said jaws than the other; said jaws being formed with cam surfaces adapted to bear against the upper surface of the rail base, whereby movement of the yoke in one direction transversely of the rail distorts the yoke and brings said jaws and said bearing surface into gripping engagement with the rail base.

8. A rail anchor comprising a yoke member formed with jaws for engaging opposite edges of a rail base and with means for bearing against the bottom surface of the rail at a point nearer one of said jaws than the other; said jaws being formed with cam surfaces adapted to bear against the upper surface of the rail base, whereby movement of the yoke in one direction transversely of the rail distorts the yoke and brings the said jaws and said bearing surface into gripping engagement with the rail base and one of said jaws being formed with an abutment to limit the movement of the anchor to its normal applied position.

9. A rail anchor comprising a rail base embracing yoke provided with jaws formed to extend over the upper surfaces of a rail base at a greater angle than said surface of said base, the portion of the yoke intermediate said jaws being formed with means for bearing against the bottom surface of the rail nearer one jaw than the other and one of said jaws being formed at a greater angle than the other.

10. A rail anchor comprising a rail base embracing yoke provided with jaws formed to extend over the upper surfaces of a rail base at a greater angle than said surfaces and formed with abutments which bear against the vertical surfaces of the rail base, the portion of the yoke intermediate said jaws being formed with means for bearing against the bottom surface of the rail at a point nearer one of said jaws than the other and one of said jaws being formed at a greater angle than the other jaw, for the purpose described.

HAROLD G. WARR.
